(57) **CLAIM**

The ornamental design for a light shroud, as shown and described.

DESCRIPTION

FIG. 1 is a front, right perspective view of a light shroud showing the new design;

FIG. 2 is a right side view of the invention illustrated in FIG. 1;

FIG. 3 is a left side view of the invention illustrated in FIG. 1;

FIG. 4 is a rear view of the invention illustrated in FIG. 1; FIG. 5 is a front view of the invention illustrated in FIG. 1; FIG. 6 is a top view of the invention illustrated in FIG. 1; FIG. 7 is a bottom view of the invention illustrated in FIG. 1; and,

FIG. 8 is a front, right perspective view of the invention illustrated in FIG. 1, shown in a condition of use wherein the light shroud is shown in combination with a light source and an identification card received in a card-receiving slot of the light shroud.

The broken lines in the drawings depict environmental subject matter that forms no part of the claimed design.
